STAMPING DEVICE

Marion D. Linn, Whiteriver, Ariz.

Application April 16, 1935, Serial No. 16,715

1 Claim. (Cl. 101—3)

This invention relates to a device which is mainly intended for stamping tags and bands, the general object of the invention being to provide a plier like device having means for removably holding a die plate on one jaw so that a band or tag placed between the jaws will be stamped by the die when the jaws are moved together.

Another object of the invention is to provide means whereby the die member can be easily and 10 quickly put into place or removed.

This invention also consists in certain other features of construction and in the combination and arrangement of several parts, to be herein-after fully described, illustrated in the accompanying drawings and specifically pointed out in the appended claim.

In describing the invention in detail, reference will be had to the accompanying drawings wherein like characters denote like or corresponding parts throughout the several views, and in which:—

Figure 1 is an elevation of the device.

Figure 2 is a top plan view thereof.

Figure 3 is a bottom plan view of the lower jaw 25 member.

Figure 4 is a fragmentary bottom plan view of the upper jaw member with a die member in position.

Figure 5 is a similar view with the die member 30 removed.

Figure 6 is a section on the line 6—6 of Figure 1.

Figure 7 is a face view of a die member.

Figure 8 is a perspective view thereof.

35 In these drawings the numeral 1 indicates the upper jaw member and the numeral 2 the lower jaw member, these members being provided with the handle parts 3 and the two members are pivotally connected together as shown at 4. As

40 it will be seen the device is somewhat in the form of a pair of pliers. The upper jaw member is formed with the depending part 1' the lower face of which is formed with the guideway 5 which is formed with the laterally extending part 5' at

45 one end thereof, this guideway being adapted to receive the die plate 6 which is formed with the wings 7 at one end thereof, the inner edges of which form shoulders for fitting into the parts 5' and the outer edge of which is formed with

50 a double curve forming a central recess 8. A rod 9 has a sliding fit in a hole 10 formed in the part

1' and at one end has a wing-shaped head 11, a portion of which is adapted to fit in the recess 8 to hold the die plate in position with the wings 7, thus engaging the shoulders formed by the parts 5'. A spring 12 encircles a portion of the member 9 and has one end bearing against the jaw and its other end against a washer 13 held in place by a pin 14.

The upper face of the jaw 2 is flat having an upstanding part 15 thereon and the under face 10 is beveled as shown at 16 in Figure 3.

As it will be understood a plurality of the die plates are provided and when a plate is to be used it is simply placed in the guideway 5 with the inner edges of the wings 7 fitting in the parts 15 5' of the guideway and then the member 9 is turned to cause a portion of the head 11 to engage the recess 8 as shown in Figures 1 and 4. Thus the die plate is yieldingly held in position and can be readily removed by pulling outwardly 20 upon the head 11 and then turning the member 9 so as to move the head to one side of the die plate.

The member to be stamped is placed on the jaw 2 under the die plate and then the handles are 25 pressed together to cause the die plate to engage the member and if desired the jaw 1 can be struck with a hammer or the like to cause the die plate to properly mark the object.

It is thought from the foregoing description 30 that the advantages and novel features of the invention will be readily apparent.

It is to be understood that changes may be made in the construction and in the combination and arrangement of the several parts, provided 35 that such changes fall within the scope of the appended claim.

What is claimed is:—

A stamping device comprising a supporting member having a guideway therein formed with laterally extending parts at one end thereof, a die plate having its side edges engaging the guideway and provided with laterally extending wings for engaging said end parts, the wing carrying part of the plate having a recess therein, a rod 40 slidably supported by the supporting member and having a head for engaging the recess to hold the plate in position and a spring on the rod for normally holding the same in position with the head in engagement with the recess. 45
